UNITED STATES PATENT OFFICE.

STEPHEN HUGH HALE, OF KANSAS CITY, MISSOURI.

DEVICE FOR AND METHOD OF MIXING GAS AND AIR FOR COMBUSTION.

1,249,382.

Specification of Letters Patent. Patented Dec. 11, 1917.

Application filed April 5, 1915. Serial No. 19,306.

To all whom it may concern:

Be it known that I, STEPHEN H. HALE, a citizen of the United States, residing at Kansas City, in the county of Jackson and State 5 of Missouri, have invented certain new and useful Improvements in Devices for and Methods of Mixing Gas and Air for Combustion, of which the following is a specification, reference being had therein to the 10 accompanying drawing.

This invention relates to improvements in gas and air mixing and delivering devices. One of the objects of the invention is to provide devices which are so constructed and 15 have their parts so related that the flame produced in the combustion region will have its most efficient part constantly maintained in a given predetermined position notwithstanding such variations as may be made in 20 the quantity of gas which is introduced to the mixer and then to the burner.

Heretofore, in mixing, controlling and burner mechanisms there has not, to my knowledge, been provision made for modifying the character of the flame and simultaneously maintaining at predetermined points the efficient parts thereof. Numerous devices have been used, and others proposed, for varying the quantity of air in 30 relation to the quantity of gas that is being consumed at successive times. But I have found that this is by no means sufficient in order to make available to the utmost the heat which is generated by the combustion. 35 It is well known, as concerns gas flames, and can be readily observed, that each comprises two distinctly defined sub-flames, each approximating, in general shape, a conical conformation, one being termed the "inner" 40 cone and the other the "outer" cone; matters which will be referred to more fully below.

It is further well established that, in respect to a vertically disposed flame, there 45 is one horizontal plane where it develops the extreme of available heat, and that a superjacent object positioned to have a surface lying in that plane will receive and absorb to the greatest degree the heat units generated. In flames that are quite common (those having an inner cone of two and a half inches) this plane is about one-quarter of an inch (with variations) above the apex of the inner cone. The position of this 50 plane at any instant depends upon the char-

acter of the combustible gas and upon the proportion of the air (the efficient part of which is the oxygen component) that is commingled with the gas and is delivered to the interior of the flame. As the quantity 60 of oxygen-carrying air which reaches the interior of the flame (generally termed the "primary" air) relatively increases or decreases, the inner cone (and with it the outer) lengthens or shortens, and the position of the plane above referred to (which will be herein termed the "heat zone") is correspondingly carried upward or downward.

One of the objects of the present invention is as above noted to introduce into the assemblage of parts which effect the admitting and the mixing of the gas and air, factors which will insure that at all times the heat zone shall constantly remain in one 75 relative position within approximately fixed limits.

Another object of the invention is to provide parts by which, when a maximum volume of mixture is being delivered and consumed at the burner, its constituents shall be in predetermined proportion, and by which, as the gas is reduced in volume, the air will also be continually reduced but at a rate which is greater than the rate of decrease in gas.

In the drawings:

Figure 1 is a plan view of a portion of a gas stove having parts embodying my improvements.

Fig. 2 is a section on the line 1—1 of Fig. 1.

Fig. 3 is a vertical section, on a larger scale, of the parts which control the gas and air that are introduced to the mixing chamber.

Fig. 4 is a side view of the parts in Fig. 1.

Fig. 5 is a top view.

Figs. 6, 7 and 8 are diagrams.

Fig. 9 is a partial side view of a mixer 100 and burner, showing also the flames resulting from different adjustments of the regulating devices.

1 indicates a mixing chamber, 2 a gas supply duct connected to the manifold 2^a; 3 a 105 gas valve bearing or socket, 4 the gas valve therein, 5 a nipple or short duct extending laterally from the valve socket 3; 6 a delivery nozzle extending from the nipple 5 toward the mixing chamber 1; 7 a tube sur- 110

rounding the nozzle 6 and secured to the nipple 5, and at the other end fastened to the mixing chamber 1. 11, 11 are air orifices in the tube or casing 7, each orifice having a wide end edge 12, converging side edges 13 and an apex 14. 15 indicates the burner which is shown as being a tube section at right angles to the tube of the mixing chamber 1, and having opening 17 through which pass the gases to be inflamed. 18 indicates the flame as an entirety, the line 19 passing therethrough indicating the plane of highest available heat or the high "heat zone." 15 This flame is shown as composed of the inner cone 20 and the outer cone 21. The inner cone is produced by the partial combustion or oxidizing of the carbon of the mixture and, generally, also of a minor portion of the hydrogen, the principal result of the chemical reaction at the surface of this cone being the production of carbon monoxide (which becomes visible at that surface) together with a small amount of 25 water vapor. The oxygen that effects these reactions in this region is that which is carried in with the "primary" air entering the mixing chamber through ports 11 and passing with the hydrocarbon gas to the 30 burner mouth. The carbon monoxide water vapor and remaining hydrogen pass from the inner cone 20 outward and, being highly heated, they unite with oxygen derived from the surrounding mass of atmospheric air, the quantum of oxygen so derived being sufficient to carry the carbon monoxide into the carbon dioxide form and also effect the complete oxidizing of the hydrogen, that is, assuming that the combustion has 35 been carried suitably far at the inner cone.

The oxygen required for complete combustion of hydrocarbon gases (of the characters commonly used for fuel) is that which is found in a volume of atmospheric air that is approximately ten times the volume of the gas to be burned. A relatively small part of this oxygen is taken in with the primary air, and the larger quantity is supplied from the atmosphere surrounding the 45 flame, termed the "secondary" air. These relative volumes of primary air (with its oxygen) and of the secondary air, I have found must be varied to correspond with different fuel gases in order to utilize, with the utmost economy, the heat units resulting from the combustion.

For certain common grades of fuel gas (such as numerous natural gases composed largely of methane) I have found that of 50 the total ten volumes of atmospheric air required for complete combustion (in relation to a unit volume of gas) approximately three and a half volumes should be taken in as primary air and mixed with the gas before it reaches the flame region, that is,

when the maximum quantity of gas is flowing and burning, while the other six and a half, approximately, volumes of air (or the oxygen content of that volume) will be freely derived from the atmosphere surrounding the flame. I have further found that when the gas is flowing at any rate lower than the possible maximum, I can attain sufficiently complete combustion of it if the volume of primary air be reduced to, but 70 not materially below, about two and a half times that of the reduced quantity of gas. In such case, the secondary oxygen is derived from about seven and a half volumes of the flame-surrounding atmosphere. But 75 there are manifest limits in this matter of varying the relative proportions of the primary and the secondary air masses.

The best results, as concerns complete combustion of the various possible flows of 80 gas, can be attained, as I have discovered, only by nicely proportioning that part of the total quantity of necessary oxygen which passes through the mixing tube and thence to the interior of the flame region, on 85 the one hand, and that part of the total quantity which is to be derived from the atmosphere surrounding the flame. If the volume of primary air, in relation to the volume of gas which is passing at any time 90 becomes too great there is danger of back firing into the mixing chamber. If, on the other hand, the air at any adjustment of gas is too low, more or less of the carbon of the gas passes beyond the inner cone 95 surface without oxidizing to the monoxide form, and this cone becomes yellow, and this is followed by delivery of too much carbon to one part or another of the outer flame cone.

Turning to the drawings, I have indicated, conventionally, in Fig. 9, by lines 100 at 20 and 21, as aforesaid, what I am referring to as the flame cones which are produced at the time of the complete combustion of a maximum mixture passing through 105 a mixer and burner of substantially the dimensions indicated, the gas having a pressure of from one to three ounces.

In using any gas burner of the ordinary 110 sorts under the conditions indicated, a flame of this character can be produced. Moreover, all earlier burners have been adapted to cut down the flow of gas by valve devices or their equivalent. And in some cases it has been 115 proposed to simultaneously vary the flow of gas and the inflow of air. But in all cases, so far as known to me, where there was a simultaneous modifying of both the gas flow and of the air flow, the parts have been 120 so constructed and related that the air flow either was decreased without any predetermined relation at all of the flow of air to the flow of gas, or else was decreased at a rate 125 substantially equal to the rate of decrease of 130

the gas, the ratio between the volumes in the latter cases being constant. And my observations of earlier devices of all sorts in this class have shown me that when they were in 5 operation and the gas supply was decreased from the maximum, the simultaneously decreased air volume was varied in such way as to produce disadvantageous flame characteristics. That is to say, in all cases that I 10 have observed, the cutting down of the gas has been followed immediately by a shortening of the inner flame cone 20 as well as the outer cone 21. No provision has been heretofore made for simultaneously modifying 15 the air supply in relation to the decreasing gas supply in such way that the length, vertically, of the inner flame cone (and, with it, the zone 19 of highest heat) will remain practically fixed, irrespective of the quantity 20 of gas flowing to the flame region.

The lengths of the flame cones and the position of the heat zone 19 are established (with a gas of given constitution and pressure) by the above described relative proportions of primary air and secondary air, or, 25 in other terms, in proportion to the quantities of oxidizing work that are being effected at the flame cone surfaces respectively. Thus, if the supply of primary air and its 30 oxidizing efficiency be reduced, while the gas supply is constant, the inner part 20 of the flame instantly responds by lengthening upward that it may avail itself of more secondary oxygen. Vice versa, if the quantity of primary air, with its oxygen, should be, at any 35 time, increased while the gas remains the same at the burning points, the flame cone 20 quickly answers by shortening, vertically, as it then requires less oxygen from the secondary, or outer, air. Thus it will be seen that, to 40 maintain the highest heat zone 19 in a fixed plane vertically, the above mentioned nicety of proportioning of the primary and the secondary air supplies must, at all times, be 45 attained. And it will be also seen that as the flow of gas is reduced in volume at the burning points (which, as above explained, is followed by lowering the flame cone 20 and the heat zone 19) the air commingled therewith 50 must not only be also reduced in relative volume, but must be reduced at a relatively greater rate; which variation in rates, however, should always keep the ratio of the two gas volumes between those limits, above 55 noted, where perfect combustion is attainable.

For example, if the quantity of air mingled with the gas, at the time of complete combustion of the maximum gas supply, is 60 in the ratio of approximately three and a half of air to one volume of gas, as above described, it will still be possible to have practically complete combustion with a somewhat smaller relative volume of air passing 65 through the mixer, because the balance of

the requisite oxygen, as above described will be then derived from the secondary or surrounding atmosphere.

And the same is true of a mixture wherein the quantity of gas is decreased from the maximum. For example, if the gas should be cut down, say, two-thirds of the possible maximum, the volume of the air can be simultaneously cut down to two-thirds of the maximum of air which flows at the time of 70 complete combustion of the maximum; but, as above noted, the flame cones will be shortened and the heat zone 19 will be lowered, although complete combustion is occurring. But I aim to have the heat zone fixed. Consequently, when I cut down the gas to two-thirds of its possible maximum I prevent the flame from shortening and the heat zone from lowering by supplying less than two-thirds of the maximum possible primary air, 75 this smaller quantity of air causing the length of the inner part 20 of the flame and the heat zone to remain fixed.

And, for further illustration, if the gas volume is further reduced to, say, one-fourth 80 of its possible maximum it is necessary (in order to keep the flame cone and the heat zone in their predetermined positions) to lower the volume of mixture air to a quantity considerably below one-fourth of the 85 possible maximum primary air in order to induce the flame cone 20 to elongate itself relatively to the quantities of gas in its effort to secure sufficient oxygen.

In coming down thus from the possible 90 maximum quantities of gas and air to, say, two-thirds, and then to, say, one-fourth of such maximum quantities, I have found that the rate at which the air decreases in relation to the rate of gas decrease is not a constant, but an increasing, one.

Of course, the upper and the lower limits defining complete combustion must be had in mind. As already observed at no point should the air be decreased in relation to the gas to an extent beyond the lower limit for a combustion at the surface of the inner cone as complete as is desired at that place; for if that limit be passed in decreasing the rate of primary air at any point the flame, instead of maintaining its predetermined length with complete combustion, will elongate upward in its effort to find secondary oxygen and will at once display unconsumed yellow carbon.

As above remarked, I have found that at any point in descending from the maximum quantities of gas flow, I can attain practically complete combustion until the proportion of the air has been lowered to approximately two and a half volumes to a unit volume (at that point of supply) of gas.

This regulating of the primary air and varying its rate of decrease in relation to the decrease in the flow of gas are accom-

plished by devices constructed and relatively arranged as shown in the drawings.

The gas valve 4 is rotated in its seat 3 by means of a handle 22. The air valve is a sleeve 23 fitted to the exterior of the tube 7 and adapted to cover and to open the air orifices 11. 24 is a link which connects the air valve to a crank arm 25 secured to the handle 22 or to the stem of the valve 4.

10 The gas valve 4 when fully open as shown in Fig. 3 permits the maximum flow of gas. The latter enters the nozzle 6 and escapes from the reduced orifice 6^a therein at a comparatively high velocity. The air orifices 11 are cut peculiarly so that their wider ends 12, their tapering sides 13 and their apices 14 insure that when the valve 23 is in its extreme open position as in full lines, Fig. 9, the air will enter at a predetermined maximum rate, which rate (having in mind the assumptions in the above illustrations) will be such that at the flame region there will be supplied three and a half volumes of primary air to one volume of gas, and the flame cones then produced can be regarded as illustrated by the lines at 20 and 21, Fig. 9.

If now it be desired to cut down the flow of gas to, say, two thirds of its maximum, the gas valve handle 22 is turned to bring 30 the gas valve to the position, approximately, shown in Fig. 6. The link 24 causes the air valve sleeve 23 to move to the position in Fig. 6. And the air orifices 11 are so formed (as concerns their length, their width at 12, 35 and the angle of divergence of their side edges 13) that, (in conjunction with the predetermined relations of the crank arm 25, the link 24 and the valves 4 and 23) when the valve 23 is in the position shown in Fig. 40 6, it cuts down the flow of air to a quantity considerably less than two-thirds of the maximum of air. These air orifices are carefully designed in relation to the injector action of the gas jet. The lateral dimensions of the 45 air orifices vary from line to line transversely, each orifice narrowing in a backward direction relatively to the path of the gas. As more and more gas is admitted its in-drawing power is increased, 50 and therefore the cross area of the air orifices is relatively decreased; in other words, more air is drawn through a relatively small increase in air entrance area as the air valve opens because of the gradually increasing efficiency of the gas as a factor in drawing in the air. Inasmuch as gas pressures vary when that from one locality or from one source of supply is compared with another, it is impossible to lay down any 55 positive data for the dimensions of the air orifices 11; these are determined from the several governing data, including the constitution of the gas and the pressure at which it is supplied. The devices for storing and conducting gas and supplying it to,

and controlling it at, the burners are generally standard and duplicates of each other. Consequently gas is delivered and burned at an elevated point, say at Denver, Colorado, for example, with the same devices as those with which it is delivered and burned at sea level, for example, at New York. But the error here involved is apparent upon mention, as no difference in the pressures is taken into consideration. 70 Because of these differences in the devices, there will be a difference in the quantity of gas consumed at one place when passed through, and controlled by a certain set of devices, when compared with the quantity 80 consumed at another place, where it passes through duplicate devices, so far as concerns the production of a given amount of heat.

One of the objects of my invention is to 85 provide devices which will supply, and control, gas at the time of consumption in such way that, regardless of the level of the place where consumed, the full amount of possible heat will be generated by so varying the 90 air inlets and the air controlling devices that the necessary quantities of the two bodies will be provided for perfect combustion.

Consequently the flame cone 20, instead of 95 shortening, will remain with approximately the length shown in Fig. 9 and the heat zone 19 will remain in the same position. If the air valve 23, and its moving parts, and the air orifices 11 had been so related that the 100 front edge of the valve 23 would have stopped at, say, the line y—y Fig. 6 (the line at which two-thirds of the maximum of air would enter the ports 11), the flame cone 20 would have shortened and the heat zone 105 19 would have dropped. But with the parts constructed as described the decrease in air is relatively greater than the decrease in gas, and therefore the cone 20 must extend upward to derive secondary oxygen. 110

The lines 20^a can be regarded as indicating the defining lines of the inner flame cone when the gas and air are reduced with the peculiar relationship in volumes attained by the devices shown in Fig. 6. The inner 115 flame cone at 20^a is thinner than that indicated by 20, but is of the same length vertically. At such time the outer part 21 of the flame is considerably reduced in size and its boundary lines may be regarded as indicated at 21^a.

In Fig. 7 I have shown diagrammatically the relative positions of the controlling devices for the gas and the air when the gas is cut down to say one-quarter of its possible 125 maximum. The air valve 23 is then advanced over the orifices 11 in the manner illustrated in this Fig. 7. If it were to stop at the line z—z Fig. 7, one-half of the possible maximum of air would enter; but in 130

the gas, the ratio between the volumes in the latter cases being constant. And my observations of earlier devices of all sorts in this class have shown me that when they were in 5 operation and the gas supply was decreased from the maximum, the simultaneously decreased air volume was varied in such way as to produce disadvantageous flame characteristics. That is to say, in all cases that I 10 have observed, the cutting down of the gas has been followed immediately by a shortening of the inner flame cone 20 as well as the outer cone 21. No provision has been heretofore made for simultaneously modifying 15 the air supply in relation to the decreasing gas supply in such way that the length, vertically, of the inner flame cone (and, with it, the zone 19 of highest heat) will remain practically fixed, irrespective of the quantity 20 of gas flowing to the flame region.

The lengths of the flame cones and the position of the heat zone 19 are established (with a gas of given constitution and pressure) by the above described relative proportions of primary air and secondary air, or, in other terms, in proportion to the quantities of oxidizing work that are being effected at the flame cone surfaces respectively. Thus, if the supply of primary air and its 25 oxidizing efficiency be reduced, while the gas supply is constant, the inner part 20 of the flame instantly responds by lengthening upward that it may avail itself of more secondary oxygen. Vice versa, if the quantity of primary air, with its oxygen, should be, at any 30 time, increased while the gas remains the same at the burning points, the flame cone 20 quickly answers by shortening, vertically, as it then requires less oxygen from the secondary, or outer, air. Thus it will be seen that, to 35 maintain the highest heat zone 19 in a fixed plane vertically, the above mentioned nicely proportioning of the primary and the secondary air supplies must, at all times, be 40 attained. And it will be also seen that as the flow of gas is reduced in volume at the burning points (which, as above explained, is followed by lowering the flame cone 20 and the heat zone 19) the air commingled therewith 45 must not only be also reduced in relative volume, but must be reduced at a relatively greater rate; which variation in rates, however, should always keep the ratio of the two gas volumes between those limits, above 50 noted, where perfect combustion is attainable.

For example, if the quantity of air mingled with the gas, at the time of complete combustion of the maximum gas supply, is 55 in the ratio of approximately three and a half of air to one volume of gas, as above described, it will still be possible to have practically complete combustion with a somewhat smaller relative volume of air passing 60 through the mixer, because the balance of

the requisite oxygen, as above described will be then derived from the secondary or surrounding atmosphere.

And the same is true of a mixture wherein the quantity of gas is decreased from the maximum. For example, if the gas should be cut down, say, two-thirds of the possible maximum, the volume of the air can be simultaneously cut down to two-thirds of the maximum of air which flows at the time of 75 complete combustion of the maximum; but, as above noted, the flame cones will be shortened and the heat zone 19 will be lowered, although complete combustion is occurring. But I aim to have the heat zone fixed. Consequently, when I cut down the gas to two-thirds of its possible maximum I prevent the flame from shortening and the heat zone from lowering by supplying less than two-thirds of the maximum possible primary air, 80 this smaller quantity of air causing the length of the inner part 20 of the flame and the heat zone to remain fixed.

And, for further illustration, if the gas volume is further reduced to, say, one-fourth 90 of its possible maximum it is necessary (in order to keep the flame cone and the heat zone in their predetermined positions) to lower the volume of mixture air to a quantity considerably below one-fourth of the 95 possible maximum primary air in order to induce the flame cone 20 to elongate itself relatively to the quantities of gas in its effort to secure sufficient oxygen.

In coming down thus from the possible 100 maximum quantities of gas and air to, say, two-thirds, and then to, say, one-fourth of such maximum quantities, I have found that the rate at which the air decreases in relation to the rate of gas decrease is not a constant, but an increasing, one.

Of course, the upper and the lower limits defining complete combustion must be had in mind. As already observed at no point should the air be decreased in relation to the gas to an extent beyond the lower limit for a combustion at the surface of the inner cone as complete as is desired at that place; for if that limit be passed in decreasing the rate of primary air at any point the flame, instead of maintaining its predetermined length with complete combustion, will elongate upward in its effort to find secondary oxygen and will at once display unconsumed yellow carbon.

As above remarked, I have found that at any point in descending from the maximum quantities of gas flow, I can attain practically complete combustion until the proportion of the air has been lowered to approximately two and a half volumes to a unit volume (at that point of supply) of gas.

This regulating of the primary air and varying its rate of decrease in relation to the decrease in the flow of gas are accom-

plished by devices constructed and relatively arranged as shown in the drawings.

The gas valve 4 is rotated in its seat 3 by means of a handle 22. The air valve is a sleeve 23 fitted to the exterior of the tube 7 and adapted to cover and to open the air orifices 11. 24 is a link which connects the air valve to a crank arm 25 secured to the handle 22 or to the stem of the valve 4.

10 The gas valve 4 when fully open as shown in Fig. 3 permits the maximum flow of gas. The latter enters the nozzle 6 and escapes from the reduced orifice 6^a therein at a comparatively high velocity. The air orifices 11 are cut peculiarly so that their wider ends 12, their tapering sides 13 and their apices 14 insure that when the valve 23 is in its extreme open position as in full lines, Fig. 9, the air will enter at a predetermined maximum rate, which rate (having in mind the assumptions in the above illustrations) will be such that at the flame region there will be supplied three and a half volumes of primary air to one volume of gas, and the flame cones then produced can be regarded as illustrated by the lines at 20 and 21, Fig. 9.

If now it be desired to cut down the flow of gas to, say, two thirds of its maximum, the gas valve handle 22 is turned to bring the gas valve to the position, approximately, shown in Fig. 6. The link 24 causes the air valve sleeve 23 to move to the position in Fig. 6. And the air orifices 11 are so formed (as concerns their length, their width at 12, 35 and the angle of divergence of their side edges 13) that, (in conjunction with the pre-determined relations of the crank arm 25, the link 24 and the valves 4 and 23) when the valve 23 is in the position shown in Fig. 40 6, it cuts down the flow of air to a quantity considerably less than two-thirds of the maximum of air. These air orifices are carefully designed in relation to the injector action of the gas jet. The lateral dimensions of the 45 air orifices vary from line to line transversely, each orifice narrowing in a backward direction relatively to the path of the gas. As more and more gas is admitted its in-drawing power is increased, 50 and therefore the cross area of the air orifices is relatively decreased; in other words, more air is drawn through a relatively small increase in air entrance area as the air valve opens because of the gradually increasing efficiency of the gas as a factor in drawing in the air. Inasmuch as gas pressures vary when that from one locality or from one source of supply is compared with another, it is impossible to lay down any 55 positive data for the dimensions of the air orifices 11; these are determined from the several governing data, including the constitution of the gas and the pressure at which it is supplied. The devices for storing and conducting gas and supplying it to,

and controlling it at, the burners are generally standard and duplicates of each other. Consequently gas is delivered and burned at an elevated point, say at Denver, Colorado, for example, with the same devices as those with which it is delivered and burned at sea level, for example, at New York. But the error here involved is apparent upon mention, as no difference in the pressures is taken into consideration. 70 Because of these differences in the devices, there will be a difference in the quantity of gas consumed at one place when passed through, and controlled by a certain set of devices, when compared with the quantity 80 consumed at another place, where it passes through duplicate devices, so far as concerns the production of a given amount of heat.

One of the objects of my invention is to 85 provide devices which will supply, and control, gas at the time of consumption in such way that, regardless of the level of the place where consumed, the full amount of possible heat will be generated by so varying the 90 air inlets and the air controlling devices that the necessary quantities of the two bodies will be provided for perfect combustion.

Consequently the flame cone 20, instead of 95 shortening, will remain with approximately the length shown in Fig. 9 and the heat zone 19 will remain in the same position. If the air valve 23, and its moving parts, and the air orifices 11 had been so related that the 100 front edge of the valve 23 would have stopped at, say, the line y—y Fig. 6 (the line at which two-thirds of the maximum of air would enter the ports 11), the flame cone 20 would have shortened and the heat zone 105 19 would have dropped. But with the parts constructed as described the decrease in air is relatively greater than the decrease in gas, and therefore the cone 20 must extend upward to derive secondary oxygen. 110

The lines 20^a can be regarded as indicating the defining lines of the inner flame cone when the gas and air are reduced with the peculiar relationship in volumes attained by the devices shown in Fig. 6. The inner 115 flame cone at 20^a is thinner than that indicated by 20, but is of the same length vertically. At such time the outer part 21 of the flame is considerably reduced in size and its boundary lines may be regarded as indicated at 21^a.

In Fig. 7 I have shown diagrammatically the relative positions of the controlling devices for the gas and the air when the gas is cut down to say one-quarter of its possible 125 maximum. The air valve 23 is then advanced over the orifices 11 in the manner illustrated in this Fig. 7. If it were to stop at the line z—z Fig. 7, one-half of the possible maximum of air would enter; but in 130

such case the inner flame cone would drop because of the full supply of primary oxygen. But as this air valve 23 is at this time carried beyond the line $z-z$, the quantity 5 of primary oxygen is reduced, relatively, and the inner flame cone 20 is reduced to relatively elongate itself so that its tip remains approximately in its earlier position and the heat zone at 19 is not lowered. Of course the flame cone 20 becomes considerably thinner or narrower as indicated at 20^b. And the outer part of the flame contracts and shortens and can be regarded as illustrated by the lines at 21^b.

10 In Fig. 8 there are illustrated at 11^a air orifices of such sort that the air would be reduced at a rate in a constant ratio with the rate of the reduction of gas, and consequently the flame at 20 and the heat zone 15 would be thrown out of their desired positions. The velocity of the gas escaping through the nozzle at 6 is one of the most important factors governing the quantity and rate of air supply; this velocity varying 20 with the flow of gas. And the orifices 25 11 are formed so as to be peculiarly related to the velocity of the entering gas. If they were made of the shape and size indicated at 11^a in Fig. 8, (the velocity of the gas remaining the same) too much air would be 30 drawn in at any adjustment for gas. There is, indeed, a predetermined margin allowed in the capacity of the ports 11, this being governed also by the throw of the valve 23, 35 in order to provide for relatively minor variations in the pressure and velocity of the gas.

I am aware, as above indicated, that it has been heretofore proposed to construct a 40 gas mixing and burning device of the "Bunsen burner" class and to employ a sleeve shutter to slide over air openings adjacent to the gas inlet, these shutters or valves being connected to the plug valve for the gas 45 by a link and crank union. But the air orifices were differently constructed, and the air shutters or valves were merely used to quickly open and quickly close the entire air orifice.

50 I am also aware that among the devices so proposed have been some in each of which there was to be provided a rotary gas element provided with a series of graduated apertures or with a series of sets of such 55 apertures; the gas to flow, first, through a small aperture, and then, on moving the valve, to be cut off until a larger aperture registered with the passage, then cut off again until a still larger aperture registered, 60 and so on. But I believe myself to be the first to have arranged the gas feeding and air supplying devices, and their controllers, in such way that when the gas is to be cut down from its maximum the air is simultaneously and automatically cut down with- 65

out interrupting the flow or velocity of the gas and the gas flow remaining continuous at all times while the air is flowing; and the first to provide devices for cutting down the flow of gas and simultaneously cutting 70 down the flow of air, but at a rate greater than the rate of decrease of the gas, and the parts so proportioned that the most efficient part of the flame is maintained in approximately one position, vertically. I have herein, for the sake of illustration and description, assumed proportions of gas volumes, pressures of gas, heights of flames, etc., but do not mean to be understood as limiting the essential features of the invention to the 75 specific data so assumed for the purposes of description.

What I claim is:

1. The combination of the mixing chamber, a duct adapted to deliver varying quantities of gas mixture therefrom to the combustion region, and two simultaneously acting gas control devices, one adapted to supply gas at a maximum rate to the mixing chamber and to decrease the supply of gas at 80 a fixed rate, and the other adapted to deliver air to said chamber at a maximum rate, and to decrease the air supply at a fixed rate greater than the rate at which the gas is simultaneously decreased.
2. The combination of the mixing chamber, a burner supplied therefrom and adapted to form a combustion flame with a fixed heat zone and two simultaneously acting gas control devices one adapted to supply gas at 85 a maximum rate to said chamber to produce a flame having said heat zone and also adapted to supply gas at either of several lower rates, and the other control device being adapted to supply air at a maximum rate to maintain a maximum flame having said heat zone and also adapted to supply air at lower rates respectively corresponding to said lower rates of gas supply, said lower rates of air supply, respectively, being such as to maintain the same heat zone that is produced at maximum combustion.
3. The combination of the mixing chamber, a duct adapted to deliver varying quantities of mixture therefrom to a combustion 90 region and two simultaneously acting gas control devices, one adapted to supply gas to the mixing chamber at a minimum rate for combustion and also adapted to increase at a fixed rate the supply of gas, and the other adapted to deliver air to said chamber at an increasing rate which is less than the rate at which the gas is simultaneously increased, the relative quantities of gas and air permitted by said simultaneously acting control devices to enter the mixing chamber being such as to insure complete combustion at all 95 times.
4. The herein described method of producing a combustion flame with varying 100

quantities of combustible gas and establishing a fixed heat zone therefor, consisting in mixing volumes of air and combustible gas, delivering the mixture to the flame region, decreasing the gas supply at a fixed rate, simultaneously decreasing the air supply and establishing a rate of decrease for the air relative to the rate of decrease of the gas

that prevents the displacing of the heat zone of the flame.

In testimony whereof, I affix my signature, in presence of two witnesses.

STEPHEN HUGH HALE.
